WATER CLOSET

Cary J. Weaver, Goose Creek, Tex.

Application April 8, 1937, Serial No. 135,771

2 Claims. (Cl. 4—218)

This invention relates broadly to water closets and has for its primary object to provide a closet which embodies therein means for exhausting gases and odors therefrom during the operation 5 of flushing; and the invention together with its objects and advantages will be best understood from a study of the following description taken in connection with the accompanying drawings wherein:—

10 Figure 1 is an enlarged sectional view through a toilet room illustrating the invention.

Figure 2 is a vertical sectional view through a hopper provided with a ventilating opening in accordance with the present invention.

15 Figure 3 is a fragmentary elevational view of the flush tank illustrating certain details hereinafter more fully referred to.

Figure 4 is a fragmentary top plan view of the hopper also illustrating certain details herein- 20 after more fully referred to.

Referring to the drawings by reference numerals it will be seen that 5 indicates generally a toilet room, while 6 indicates the hopper and 7 indicates the flush tank.

25 In accordance with the present invention the connection between the flush tank 7 and the hopper 6 embodies what is known as a Siamese water outlet which includes a valve casing 8 on the top of which seats the control valve 9. Connected with opposite sides of the valve 8 are fittings 10 that serve to connect the water outlet pipes 11 with the valve 8. Pipes 11 extend downwardly from the flush tank and are connected as at 12 with water inlets 13 provided in the hopper 6 so that two streams of water are directed into the hopper for flushing the latter.

30 Further in accordance with the present invention the hopper 6 at the back thereof and as clearly shown in Figure 2 is provided with a venti- 35 lating opening 14 in which is fitted a nipple 15

provided at one end with a flange 16 that engages the inner face or wall of the bowl 6. At its outer or free end the nipple 15 is threaded to receive a jam nut 17 that is threaded home against the bowl 6 as shown in Figure 2. 5

Connected with the threaded end of the nipple 15 is an elbow 18 that extends through the wall 19 of the toilet room 5 and within the hollow of said wall is connected with one end of a ventilating pipe 20 that extends upwardly 10 through the wall and through the roof 21 as shown in Figure 1. On its upper outer end the ventilating pipe 20 is provided with a suitable cap 22.

It will thus be seen that during the flushing 15 of the bowl 6 the odors and gases will pass from the bowl 6 through the ventilating nipple 15, elbow 18 and ventilating pipe 20 to the atmosphere.

Having thus described the invention what is 20 claimed as new is:—

1. In a water closet, a hopper provided with a ventilating opening, a nipple having an end fitting within said opening, a flange on the inner end of the nipple, a nut threaded on the outer 25 end of the nipple for drawing the flange against the inner wall of the hopper, and a ventilating pipe connected at one end thereof with said nipple.

2. In combination, a hopper, a flush tank 30 therefor, a Siamese water connection between the flush tank and the hopper for flushing the latter, said hopper being provided with a ventilating opening between the Siamese water connections, a nipple having its end secured within said opening, an elbow connected at one end with said nipple, and a ventilating pipe connected at one end with said elbow. 35
